I. A. SEIDERS.
JOURNAL BOX LID.
APPLICATION FILED OCT. 1, 1917.

Patented Mar. 26, 1918.

Irvin A. Seiders, Inventor

Attorney

UNITED STATES PATENT OFFICE.

IRWIN A. SEIDERS, OF READING, PENNSYLVANIA.

JOURNAL-BOX LID.

1,260,719.

Specification of Letters Patent. Patented Mar. 26, 1918.

Application filed October 1, 1917. Serial No. 194,204.

To all whom it may concern:

Be it known that I, IRWIN A. SEIDERS, a citizen of the United States, residing at Reading, in the county of Berks and State 5 of Pennsylvania, have invented certain new and useful Improvements in Journal-Box Lids, of which the following is a specification.

This invention relates to improvements in 10 journal box lids and it pertains more particularly to the lids of journal boxes used on rolling stock, such as railway cars.

The object in the present invention is to provide a device that will effectively prevent 15 the very harmful occurrence commonly known as a "hot box", due to the ignition of combustible gases therein by the friction of the journal.

In my present invention I have devised a 20 journal box lid by the use of which these gases will be drawn from the box by a constant suction whenever the car is in motion, and one in which the action is identical when the car is moving in either direction.

25 The invention consists of a journal box lid formed with a longitudinal passageway, which passageway is in communication, in two opposed directions, with the interior of the box on which the lid is used, while the 30 entrance of a current of air into the passageway is assured from either end, depending upon the direction of travel.

The invention is more fully described in the following specification and clearly illustrated in the accompanying drawing, in which:—

Figure 1 is a front elevation of my improved box lid.

Fig. 2 is a sectional view on line 2—2 of 40 Fig. 1.

Fig. 3 is a sectional view of line 3—3 of Fig. 1.

In the drawing:

45 The numeral 1 designates the body portion of a journal box lid of the usual shape and design, except that the lid has formed therein a tubular portion near its lower extremity, designated by the numeral 2, by means of which a longitudinal passageway is formed 50 in the lid, and this passageway 3 is formed with a downwardly extending opening 4 at each extremity, that is, the entrance to the tubular passage way is substantially at right angles to the main portion 3 thereof.

55 This passageway is formed with two op-

positely disposed inlets 5, leading from the inner wall of the lid into the passageway 3, and each opening 5 is provided with a hood 6.

With this simple air passageway through 60 the lid and provided with communication with the interior of the box on which it is used, it is evident that the movement of the car on which it is used, in either direction, will create a suction or partial vacuum in 65 the journal box, due to the passage of air through the passageway 3, and that this draft of air will draw the combustible gases from the interior of the box, through one of the openings 5 and cause it to be expelled 70 through the exit end of the passageway 3, and the action will be the same in either direction of movement of the car.

The downwardly disposed ends of the 75 passageway will prevent the settling in the passageway of particles of grit or other foreign matter, while they will permit sufficient air circulation through the passageway to thoroughly draw the objectionable gases from the box, and thus prevent ignition 80 therein.

It will be noted that the air passing through the passageway does not enter the journal box, but that it merely enters one end of the passageway and passes out of the other end, but that, by reason of the communication between the passageway and the interior of the box, this passage of air, due to the movement of the car, will draw the gases from the box and expel them through 90 the openings 4.

It is evident that the particular formation of this passageway may be varied, and that a drawing of the gases from the box may be accomplished with slightly varied outlets, and I do not desire to limit myself 95 to the exact formation shown and described, but:—

What I claim is:—

1. A journal box lid having a horizontal, 100 open ended, tubular portion formed on its outer face and provided with downwardly disposed extremities, said lid having a central opening in its inner face communicating with the tubular portion, and two oppositely disposed hoods for said central inlet. 105

2. A journal box lid having a horizontal, tubular portion formed integrally therewith, said tubular portion having an opening 110 at each end through the front face of the

lid, and an opening from the rear face of the lid substantially midway between the two outside openings.

3. A journal box lid formed with an open ended, horizontally disposed passageway whose inlet and outlet openings are on the outside of the lid, said passageway having a central communication with the interior of the box on which the lid is used and a hood 10 for said central opening.

4. A journal box lid formed with an open

ended passageway horizontally disposed on the outer face thereof and having a central opening from the inner face thereof into said passageway.

5. A journal box lid having a horizontal, open ended tubular portion formed on its outer face and a central inlet into said tubular portion from the inside of the lid and two oppositely disposed hoods for said inlet. 15 20

In testimony whereof I affix my signature.
IRWIN A. SEIDERS.
